UNITED STATES PATENT OFFICE.

RUPERT IGNATIUS FARRELL, OF MONTREAL, QUEBEC, CANADA.

AUTOMATIC GATE.

Application filed February 10, 1926. Serial No. 87,236.

The invention relates to an automatic gate, as described in the present specification and illustrated in the accompanying drawings that form part of the same.

5 The invention consists essentially of the novel features of construction pointed out broadly and specifically in the claims for novelty following a description containing an explanation in detail of an acceptable 10 form of the invention.

The objects of the invention are to avoid the many accidents that happen at railway crossings; to facilitate the closing and opening of the gates across a roadway at a level 15 crossing coincidently with the approach and departure of the railway train; to apply the operating mechanism to gates in various places; and to provide a simple and effective operating mechanism for automatically 20 closing and opening the gate.

In the drawings, Figure 1 is a vertical sectional view disclosing the operating mechanism.

Figure 2 is a plan view showing a railway 25 way and intersecting road and gates.

Figure 3 is a sectional detail of the trip arm.

Figure 4 is a plan view showing a detail 30 of the trip arm.

Figure 5 is a side view modification of the trip arm.

Like numerals of reference indicate corresponding parts in the various figures.

Referring to the drawings, the numerals 35 10 and 11 indicate tubular posts joined at the upper end by the tubular bridge 12 within which the rocker arm 13 is centrally pivoted at 14.

40 At one end the rocker arm 13 carries the weight 15 pivotally suspended by the rod 16 sliding in the bracket 17 within the tubular post 11. At the other end the rocker arm 13 is pivotally secured to the link 18, which operatively connects it to the lever 19.

45 The lever 19 is pivotally supported intermediate of its height from the wall of the tubular post 10, by the pivot bar 20, the latter being pivotally secured in the bracket 21 in lazy tong formation, an inner end bar 22 being secured at its lower end to the lever 19 by the pivot 26 and the other inner end bar 27 being pivotally secured to the fixed bracket 28, therefore by lowering the

lever 19 the lazy tong bars are drawn together which opens the gate and by raising 55 the lever 19 the lazy tong bars are spread, which closes the gate.

The operation of the lever 19 is entirely by weight, the weight 15 drawing it upwardly through the rocker arm 13 and link 18, while the weight 29 mounted on T head 30 moves said lever downwardly.

The weight 29 is suspended from one end of the cross arm 31, which is strung around suitable pulleys, and pulled to lift the weight 60 29 from the head 30 for the upward movement of the lever 19 as already explained.

The lug 34 is bevelled at the upper side 65 35 to engage the spring latch 36 on the upward movement of the lever 19 and push said latch out of the way, so that it can return and engage the underside of the lug 34 and thus hold the weight 29 to its raised position, while the gate is closed, the said latch 36 being operated by a pull on the 70 75 cable 37 secured to said latch.

The semaphore 38 is pivotally secured to the central bracket 39 and is pivotally connected by the rod 40 to the rocker arm 13, so that at each upward movement of the lever 19 to close the gate, the semaphore 36 will be moved downwardly into a warning 80 85 position. Similarly the semaphore 41 pivotally secured to the bracket 42 and lever 19 will be moved from its housing 43 on the upward movement of the lever 19.

The semaphore 44 on the opposite side of the gate structure is contained in the housing 45 and pivoted in the bracket 46 and operated by the centrally pivoted arm 47 90 and connecting rod 48 to the rocker arm 13.

It will now be seen that all the operating mechanism is supplied in the parts described, except the means for pulling the cables 33 and 37 and this may be varied 95 according to the facilities at hand. Often electrical means are at hand, especially where signal systems are in operation, but the simplest mechanical means will be described herein and this comprises a trip arm 49 supported on a post 50, and having the pulleys 51 and 52 for one or other of the aforesaid cables as the case may be.

The trip head 53 of the arm 49 is furnished with a roller 54 and a stem 54^a pivotally secured in the stationary part 55 of the 100 105

arm which is slotted accordingly, said stem terminating at its inner end in a smaller head 56 the latter being held to its outer position in box 57 by the spring 58, the fixed ring 59 5 for the cable being secured to the minor head 56 in alignment with the pulley 51.

The trip head 53 is engaged by any suitable contrivance from the train, and as the train approaches the crossing the head 53 10 is lifted and this pulls on the cable 33 which raises the weight 29 and allows the weight 15 through the rocker arm 13 to move the lever 19 in an upward direction and this 15 spreads the lazy tong bars of the gates until the gate is closed.

As the train leaves the crossing, another form of trip arm is operated to pull the cable 37 and this withdraws the spring latch 36 from its engagement from the lever 19 20 permitting the movement of the latter downwardly so that the lazy tong bars of the gate are folded to their contracted position, which is the open position of the gate.

This trip arm 60 is supported by the post 25 61 and is pivoted in the rigid arm 62, the trip head 63 being held by the spring 64 and the tail 65 being attached to the cable 37 so that on the contact of the rigid flag 66 or other projection with the head 63 the latch 30 will be operated as described and drop the weight on the lever 19.

On the other side of the gateway the guides extending outwardly from the post 11 and indicated by the numerals 67 and 68 receive 25 the gate when it is shot out from the other side and absolutely prevent any chance of the said gate shooting around and beyond the post.

What I claim is:—

40 1. In a gate, a plurality of crossed bars pivotally secured to operate in lazy tong fashion, an anchoring bracket pivotally secured to an end bar of said gate, a vertical lever pivotally secured to the coacting end bar, a latch mechanism connected with said lever, a weight bearing on the lever, a pivoted cross arm operatively connected with

said lever, and a weight connected with said cross arm.

2. In a gate, a plurality of crossed bars 50 pivotally secured to operate in lazy tong fashion, an anchoring bracket pivotally secured to an end bar of said gate, a vertical lever pivotally secured to the coacting end bar, a spring latch engaging said lever, a weight bearing on the lever, a rocker arm suspending said weight, a pivoted cross arm connected to said lever, and a weight connected to the cross arm.

3. In a gate, a plurality of crossed bars 60 pivotally secured to operate in lazy tong fashion, an anchoring bracket pivotally secured to an end bar of said gate, a vertical lever pivotally secured to the coacting end bar, a gate frame having a tubular post 65 adapted to contain said lever and a cross arm connected with said lever and pivoted in the frame, a weight bearing on said lever, an operating member for said weight, a spring latch engaging the lever, a weight 70 suspended from said cross arm and cables secured to said latch and to said operating member.

4. In a gate, a plurality of crossed bars pivotally secured to operate in lazy tong 75 fashion, an anchoring bracket pivotally secured to an end bar of said gate, a vertical lever pivotally secured to the coacting end bar, a pivoted member, a weight suspended from said pivoted member and bearing on 80 said vertical lever, a cable secured to said member for operating the weight, a spring latch engaging the lever, a cable secured to said latch for releasing the lever, and trip arms formed of rigid and pivoted parts, the 85 latter parts being spring held and having the inner ends secured to the cables respectively, and a cross arm operatively connected to said vertical lever at one end, pivoted centrally and having a weight at the other end. 90

Signed at Montreal, Canada, this 25th day of January 1926.

RUPERT IGNATIUS FARRELL.
